(57) **CLAIM**

The ornamental design for a container for a package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first perspective view of a container for package, showing the new design;

FIG. 2 is a front elevation view thereof, the rear elevation view being a mirror image thereof;

FIG. 3 is a top plan view thereof;

FIG. 4 is a bottom plan view thereof;

FIG. 5 is a right side elevation view thereof, the left side elevation view being a mirror image thereof; and,

FIG. 6 is an uncapped perspective view of FIG. 1.

The broken lines shown in FIG. 6 of the drawings illustrate portions of the container for package that are environmental structures and form no part of the claimed design.

1 Claim, 5 Drawing Sheets
